REMOVABLE WINDOW TRAY

John Frederick Livingston, Williamsport, Pa.

Application April 22, 1947, Serial No. 743,041

6 Claims. (Cl. 211—88)

1

This invention relates to trays for supporting potted plants on window sills. An object of the invention is the provision of a tray for supporting potted plants on window sills, said tray being readily removable and being applied securely to the sill without the use of nails or screws or any other kind of securing means which would disfigure the sill.

Another object of the invention is the provision of a tray for supporting potted plants on a window sill, the tray having means thereon for engagement with the usual hand lift applied to the lower bar of a window frame for retaining the tray against displacement from the sill, said tray having sufficient surface contact with the sill to insure retention of the tray thereon when the retaining means is in engagement with the hand lift.

A further object of the invention is the provision of a tray for supporting potted plants on a window sill, an adjustable arm being provided with a curved member adapted to be seated within the curved hand lift usually applied to the lower bar of a window frame, said arm being slidably mounted in a guide rising from and secured to the tray with means for securing the arm in an adjusted position, means also being employed on the arm and straddling the hand lift for preventing shifting of the tray when applied to the window sill.

The invention consists in the novel construction, arrangement and combination of parts hereinafter more particularly described and claimed.

In the drawings:

Figure 1 is a view in perspective of a tray shown as removably applied to a window sill.

Figure 2 is a transverse vertical section of the tray through the removable attaching means.

Figure 3 is a transverse vertical section of a modified form of the tray and attaching means, and

Figure 4 is a fragmentary cross section through the window frame illustrating the sliding catch associated with the tray.

Referring more particularly to the drawings, 10 designates a lower window sash having the bottom bar 11 equipped with the usual hand lifts 12. The sill 13 extends inwardly into the room of a building in a horizontal plane.

The hand lifts 12 are formed integrally with a plate 14 which is secured by means of screws 15 to the inner face of the bottom bar 11. The lifts are curved so that they may be grasped comfortably by fingers of the operator. There are usually two lifts applied to each bottom bar of a window sash.

A tray designated generally by the numeral 20 has a bottom 21 which may be flat or corrugated transversely as shown at 22. The tray has vertically or angularly disposed side walls 23 and 24 with the upper free edges rolled as shown

2

at 25 or the free edges may be reinforced in any approved manner, as with a wire-stiffening means.

A guide designated generally by the numeral 30 has a right-angular base 31 which is riveted or spot-welded at 32 to the inner surface of the bottom of the tray 20 with the guide in flat contact with the inner wall 23 of the tray. The vertical side edges 33 of the guide are inturned to provide in effect a pair of parallel grooves to receive the side edges of an arm 35. The guide has a centrally disposed vertical slot 36 for a purpose which will be presently explained.

The arm 35 also has a vertical slot 37 which aligns with the slot 36. A threaded bolt 38 having a head 39 which is in contact with the inner face of the arm is received by the slots 36 and 37. A winged nut 40 threaded onto the outer end of said bolt clamps the arm 35 in an adjusted position on the guide 30.

The upper free end of the arm 35 has a member 41 which is curved to conform to the curvature of the hand lift 12 so that said curved member will fit neatly into said hand lift. A pair of spaced ears 42 formed integrally with the curved member 41 engage opposite edges of the member 12 and prevent rocking movement of the arm 35 and likewise the tray 20 when said tray is in an operative position on the sill 13.

30 The tray is placed on the sill as illustrated with the inner longitudinal wall 23 in close association with the bottom bar 11 of the window sash 10 and with the curved member 41 in vertical alignment with the hand lift 12. The winged nut 40 has been loosened so that the arm 35 may be moved downwardly into the guide 30 to permit the reception of the curved member 41 within the hand lift 12.

With the inner wall 23 of the shelf in the position shown in Figures 1 and 2, where said wall is in snug engagement with the bottom bar 11 of the window frame 10, the arm is drawn upwardly and the curved member 41 is forced into snug engagement with the hand lift 12 with the ears 42 engaged upon opposite sides of the hand lift. The nut 40 is then tightened. The tray 20 is ready for use.

A modified form of the shelf is illustrated in Figure 3. A spring arm designated generally by 50 has a vertical portion 51 rising from a base member 31—a which is riveted or spot-welded at 32 to the corrugated bottom 22 of the shelf 20. The remainder of the arm is in the form of an ogee 52. The curved free end 53 engages beneath the curved hand-lift 12 on the bar 11 of the frame 10, with the spaced ears 42 formed integrally on said free end receiving the hand lift.

The modified form of tray is placed in position by sliding the tray 20 toward the bar 11 with the bottom of the tray riding on the sill 13 until the free end 53 of the spring arm 50 con-

tacts the hand lift 12. The free end 53 is then snapped into position under the hand lift 12 while the tray is shifted to its final position shown in Figure 3. The free end of the spring arm may be assisted into position by applying pressure to a substantially horizontal position 54 of said spring arm.

The tray 20 in Figure 3 may also be placed in position by inserting the curved free end 53 of the spring arm 50 into the curved hand lift 12 with the tray tilted at an angle to the horizontal surface of the sill 13. The tray is then moved inwardly with the inner edge of the bottom of the tray being shifted to the position shown in Figure 3. Due to the ogee formation of the spring arm, the inner end of the tray may be raised slightly when it is moved into position to prevent injury to the surface of said sill.

The tray may be made of sheet metal, aluminum, plastic or any other suitable materials. The upper free edges of the side walls 23 and 24 may be formed into a bead when the shelf is manufactured from a plastic, otherwise the edges are rolled as a protection to the hands of the operator and may have a reinforcement of wire.

The tray may have any suitable length and width. When the tray is sufficiently long to extend approximately the length of the window sill 13, two attaching arms 35 or 50 are employed for engagement with the pair of hand lifts 12 secured normally to the window frame.

The bottom of the tray is sufficiently rigid to support the weight of the plants. Furthermore, the corrugations 22 not only aid in stiffening the bottom but provide a means for watering the plants through the perforated bottom of the pots when a predetermined level of water is maintained in the pan-like tray.

In order that the tray may be supported against displacement, in the event that the window is opened, opposed ends of the tray are provided with a sliding catch 55 having a knife-like edge adapted to engage between the moulding 56 and the sash 10, as shown in Figure 4.

I claim:

1. In a window sash having a bottom bar provided with a curved hand lift, a removable tray adapted to be supported on the window sill comprising a pan-like member having a portion adjacent one side edge resting on the sill, a vertical guide secured to the bottom of the member adjacent said side edge, an arm adjustably mounted in the guide and having a curved free end adapted to be seated within the curved hand lift, means for securing the arm in an adjusted position and said tray having a sliding catch at opposite ends adapted to engage between said sash and moulding strip of the window frame.

2. In a window sash having a bottom bar provided with a curved hand lift, a removable tray adapted to be supported on the window sill comprising a pan-like member having a portion adjacent one side edge resting on the sill, a vertical guide having a base secured to the bottom of the pan-like member adjacent said side edge thereof, an arm adjustably mounted in the guide and having a curved free end adapted to be seated in and beneath the curved handlift, the guide and arm being provided with alined slots, a headed bolt received by the slots and a nut threaded on to the bolt for maintaining the arm in an adjusted position to retain the curved end of said arm in snug engagement with the hand lift, and said tray having a sliding catch at opposite ends

adapted to engage between said sash and moulding strip of the window frame.

3. In a window sash having a bottom bar provided with a curved hand lift, a removable tray adapted to be supported on the window sill comprising a pan-like member having a portion adjacent one side edge resting on the sill and an arm having one end secured to the bottom of the pan-like member adjacent said side edge and having a free end, the free end of the arm being curved and adapted to be seated in and beneath the curved hand lift for retaining the pan-like member in position on the window sill.

4. In a window sash having a bottom bar provided with a curved hand lift, a removable tray adapted to be supported on the window sill comprising a pan-like member having a portion adjacent one side edge resting on the sill, an arm having one end secured to the bottom of the pan-like member adjacent said side edge, a vertically adjustable arm mounted on the first arm and having a free end, the free end of the second arm being curved and adapted to be seated in and beneath the curved hand lift for retaining the pan-like member in position on the window sill, and a pair of ears upstanding from the free end of the second arm and engageable with opposite edges of the hand lift to prevent rocking of the second arm.

5. In a window sash having a bottom bar provided with a curved hand lift, a removable tray adapted to be supported on the window sill comprising a pan-like member having a portion adjacent one side resting on the sill, an arm rising from and connected to the bottom of the pan adjacent said side edge, and having a curved member adapted to be seated in and beneath the curved hand-lift on the bottom bar and cooperating with the window sill and the bottom of the pan-like member for retaining the last-mentioned member on the sill.

6. In a window sash having a bottom bar provided with a curved hand lift, a removable tray adapted to be supported on the window sill comprising a pan-like member having a portion adjacent one side edge resting on the sill, a vertical guide having a base secured to the bottom of the pan-like member adjacent said side edge thereof, an arm adjustably mounted in the guide and having a curved free end adapted to be seated in and beneath the curved hand lift, and ears rising from the curved end of the arm and engageable with opposite side edges of the hand lift to prevent rocking of said arm and pan-like member on the sill, the guide and arm being provided with alined slots, a headed bolt received by the slots and a nut threaded on to the bolt for maintaining the arm in an adjusted position to retain the curved end of said arm in snug engagement with the hand lift.
